UNITED STATES PATENT OFFICE

ROSCOE C. PATTISON, OF ROCHESTER, NEW YORK, ASSIGNOR TO QUENCHERY COMPANY,
OF ROCHESTER, NEW YORK

DESIGN FOR A SERVICE STATION

Application filed September 18, 1931. Serial No. 41,147. Term of patent 7 years.

To all whom it may concern:

Be it known that I, Roscoe C. PATTISON, a citizen of the United States, residing at Rochester, in the county of Monroe and State of New York, have invented a new, original, and ornamental Design for a Service Station, of which the following is a specification, reference being had to the accompanying drawings, forming part thereof.

In the drawings:

Fig. 1 is a perspective view from one side of the structure.

Fig. 2 is a similar view from another side of the structure.

Fig. 3 is a top plan view.

I claim:

The ornamental design for a service station as shown.

ROSCOE C. PATTISON.
